AUTOMOBILE HEATING STRUCTURE

Elbert L. Potter, Buffalo, N. Y., assignor to Houde Engineering Corporation, Buffalo, N. Y., a corporation of New York

Application December 2, 1938, Serial No. 243,515

6 Claims. (Cl. 237—12.3)

This invention relates to heating structure and arrangement adapted particularly for the heating of vehicles such as automobiles. The invention relates particularly to that type of heater installation in which exhaust gas, hot water, or combustion mixture is circulated through a heater core through which air to be heated is blown by a fan for delivery to the interior of the vehicle.

An important object of the invention is to provide an installation arrangement in which the heater core is readily detachably insertable along guideways into a shell or casing which is inserted through a suitable opening in the car floor to be suspended by the floor, with the core provided with an inlet and outlet for the heat producing medium, and the air propulsion fan located within the casing.

A further important object is to suspend the heater unit, comprising the casing, core, and fan, from the vehicle floor preferably below the front seat thereof, with the heated air propelled by the fan delivered from below the front seat along the floor forwardly of and rearwardly of the seat, so that adequate and uniform heating of the vehicle will result.

A further important object is to provide improved arrangement for assuring clean and fresh air supply to the fan or blower to be blown thereby through the heated core for delivery to the vehicle, the air inlet being preferably from above the running board through the sill of the front door and then through the lower portion of the front door and through a guide channel to the fan in the casing suspended below the floor.

The invention also involves other features of construction and arrangement, and all the various features are shown incorporated in the structure disclosed on the accompanying drawings, in which drawings:

Figure 1 is a side elevation more or less diagrammatically showing part of a vehicle chassis structure, the front seat, and the arrangement of the heater assembly below the car floor;

Figure 2 is an enlarged plan view of part of the chassis structure and floor and showing the arrangement of the heater assembly and the connection of the heating medium therewith;

Figure 3 is an enlarged section on plane III—III of Figure 2;

Figure 4 is an enlarged side elevation partly in section of the heater core structure; and

Figure 5 is an enlarged fragmentary view to more clearly show the application of the heater core in supporting casing.

Referring to Figures 1 and 2, the chassis struc-

ture shown comprises the guide beams 10 and 11 and the diagonal cross beams 12, while 13 indicates the floor of the car. The front seat S has a suitable supporting base such as 14.

The casing or container shell 15 preferably is of sheet metal and comprises front and rear vertical walls 16 and 17 respectively, an outer side wall 18, a bottom wall 19, and the inner side wall 20, the side wall 20 diverging from the bottom wall 19 to form an outlet passageway 21. The floor 13 of the vehicle is cut out to leave an opening 22 through which the shell 15 may be extended, the shell walls at their upper edges having outwardly deflected flanges 23 for engaging with the top of the floor so as to removably suspend the casing below the floor. The opening 22 extends laterally outwardly from the juncture portion of the chassis cross beams 12, and the inner side wall 20 is deflected to follow the outline of the opening 22 where it parallels the beams 12, as clearly shown on Figure 2.

Intermediate vertically extending portions 24 and 25 of the front and rear walls 16 and 17 of the shell 15 are deflected inwardly and have their inner walls cut away to leave opposed vertical passageways 26 and 27, with the opposed edges 28 along the sides of the passageway 26 forming guides, and the edge portion 29 alongside of the passageway 27 forming similar guides, the passageways and guides serving to receive the heat- er core structure C.

The core structure comprises an inner front header 30 and an inner rear header 31, between and through which extend the flues 32. The headers are of sheet metal and along their sides and bottoms are deflected and formed to provide front and rear side grooves 33 and 34 respectively and front and rear bottom grooves 35 and 36 respectively, and if the core is to be reversible in the shell 15, the headers may also be provided with upper guide grooves 37 and 38 respectively. By means of these guide grooves, the core structure may be slipped vertically into the passages 26 and 27 of the deflected wall portions 24 and 25, with the side grooves 33 of the front inner header 30 receiving the guide edges 28, and the side grooves 34 of the rear inner header 31 receiving the guide edges 29, and with the bottom grooves of the headers receiving the bottom edges of the passageways 26 and 27 respectively, as clearly shown in Figure 5. The core structure may thus be readily slid into place in the casing or removed therefrom.

When the core is in place in the casing, the outlet passageway 21 will be at the inner side

55

thereof for outflow of heated air, and the fan or blower space 39 will be at the outer side thereof, and in this blower space is a fan or blower 40 which may be secured in any suitable manner to the outer side wall 18 of the casing 15 so as to blow air to be heated through the spaces between the flues 32 of the core. As best shown in Figure 3, the flues are slightly inclined so that the air blown therebetween by the blower will be directed diagonally upwardly into the outlet 21 for delivery to the car body.

The flues are of oblong shape, as best shown in Figure 3, and, in order to more uniformly distribute the air flow therebetween, corrugated strips 41 are interposed between the flues providing passageways and walls for guiding and distributing the air flow.

The core structure has front and rear outer headers 42 and 43, which receive the respective ends of the flues. The front outer header 42 has an inlet duct 44 to its upper portion, and an outlet duct 45 extending from its lower portion, a dividing or baffle wall 46 dividing the interior of the header into inlet and outlet spaces 47 and 48. With this arrangement the incoming heating medium flows from the upper space 47 through the flues connected with this upper space, the heating medium then flowing from the rear end of these flues through the rear header 43 and then forwardly through the flues communicating with the lower space 48 of the outer header and from there out through the outlet 45.

Referring to Figure 2, the duct 49 leads from the exhaust manifold of the vehicle engine, and 35 50 indicates the muffler structure. Between the exhaust duct 49 and the muffler I have shown a double T fitting 51 inserted whose outlet nipple 52 is connected by a duct 53 with the inlet 44 of the core structure and whose other nipple 54 is connected by a duct 55 with the outlet 45 of the core structure. Between the nipples of the fitting a valve 56 is interposed. The valve shown is mounted on a shaft 57 from which extends a lever 58 which, through a suitable operating 45 train, may be adjusted from within the vehicle by the driver. As shown on Figure 2, the valve is set to shut off direct connection between the exhaust conduit 49 and the muffler and to force the exhaust gas from the engine to flow through the 50 core structure C before reaching the muffler. When the valve is set at right angles to the position shown in Figure 2, there will be direct connection from the exhaust conduit to the muffler and only very little gas may flow through the 55 core structure.

It is obvious that, instead of using the engine exhaust as the heating medium, the water of the engine cooling system could be used as the heating medium and its flow through the core 60 structure controlled by suitable valve mechanism. Other heat producing mediums could also be used and the application and flow through the core structure properly regulated by suitable valve means.

65 To make way for the outer headers which form part of the core structure, additional openings 59 and 60 may be provided in the vehicle floor 13, and after insertion of the core structure into the casing 15, these openings may be closed by 70 covers 61 and 62 respectively.

In order to provide a fresh and clean air supply to the fan chamber 39, a deflector wall or hood 63 is shown provided terminating at its inner end over the fan compartment and having its open 75 outer end provided with a sponge rubber abut-

ment 54 to be engaged by the vehicle door 65 when the door is closed. In the bottom wall of the door sill 66 air inlet passages 67 are provided, this bottom wall being above the running board 68 and inclined away therefrom. The outer wall of the sill is provided with air passages 69 communicating with air passages 70 in the inner panel of the door, and this panel has the air passages 71 communicating with the deflector wall or hood 63 so that the air flow 1 to the fan or blower chamber is more or less tortuous, and any dust particles will be separated from the air before reaching the blower compartment.

If desired, a container 12 may be placed within 1 the door to span the air passages 70 and 71 and filled with suitable air filtering material 13, so that the air will be filtered before delivery to the blower compartment. The air supply which is taken in from the side of the vehicle over the 2 running board is blown through the core structure around the heating flues and through the outlet passage 21 into the car body below the front seat structure to be distributed forwardly 2 and rearwardly to the front and rear portions of 2 the car body for uniform heating thereof. As shown in Figure 1, the front and rear walls of the seat base 14 may be provided with openings 14 covered by grilles 15 through which the heated 3 air flows.

I thus provide a simple, economically manufactured, and efficient heating structure comprising a casing with a heating core and blower therein which may be conveniently inserted through a hole in the vehicle floor to be suspended by the floor below floor level for connection of the heater core for reception of the heating or heat forming medium under control of suitable valve mechanism, the arrangement being such that clean air is drawn in and blown 40 through the heater core for delivery of the heated air under the front seat and uniform distribution forwardly and rearwardly into the car body. By adjustment of the valving mechanism, all or part of the heating medium may 45 be available for heating purposes, or the heater may be disconnected from the heating medium, and by means of suitable electric controlling means (not shown) the operation of the blower motor can be controlled and regulated. If the 50 heater is not delivering heat, cool air may be blown into the vehicle and the temperature of the air within the vehicle may thus be regulated 55 as desired.

I have shown a practical and efficient embodiment of the various features of my invention, but I do not desire to be limited to the exact construction, arrangement, and operation shown and described, as changes and modifications may be made without departing from the scope of 60 the invention.

I claim as my invention:

1. A heater structure for automobiles comprising a box-like casing adapted for insertion downwardly through a hole in the automobile floor 65 for suspension by and below the floor, said casing having vertical guideways, a heater core slideable downwardly into said casing on said guideways, a blower within said casing at one side of said core for blowing air therethrough, 70 and an outlet passageway for the heated air terminating at floor level below the front seat of the car for distribution of heated air forwardly and rearwardly into the automobile body.

2. An automotive vehicle heater structure com- 75

prising a box-like casing insertable through a hole in the vehicle floor to depend therefrom, said casing having vertical guideways, a core structure engageable in said guideways to be guided thereby vertically into said casing, said core having flues and header structure adapted for connection for the circulation of heat producing medium through the flues, a blower within said casing at one side of said core for blowing air through said core between said flues, said casing at the other side of said core providing a discharge outlet for the heated air into the vehicle body, and means for delivering air from outside of the vehicle into the top of said casing and to said blower.

3. In an automotive vehicle, a heater structure therefor comprising a box-like casing suspended by the vehicle floor below the front seat thereof and having inlet and outlet spaces communicating with the vehicle body above the floor level, a heater core extending vertically in said casing between said inlet and outlet spaces, said core having flues adapted for connection for circulation therethrough of heat producing medium, a blower within said inlet space for blowing air around said flues into said outlet space for delivery into the car body, the door of the vehicle adjacent to the front seat having a passageway therethrough and the door sill having a passageway therethrough to the exterior of the vehicle and communicating with the door passageway, and means forming a passageway from the door passageway to said inlet space, said passageways being effective when the door is closed to supply air from the exterior of the vehicle to said inlet space to the blower therein.

4. In an automotive vehicle, a heater structure therefor comprising a box-like casing suspended by the vehicle floor below the front seat thereof and having inlet and outlet spaces communicating with the vehicle body above the floor level, a heater core extending vertically in said casing between said inlet and outlet spaces, said core having flues adapted for connection for circulation therethrough of heat producing medium, a blower within said inlet space for blowing air around said flues into said outlet space for delivery into the car body, the door of the vehicle adjacent to the front seat having a passageway therethrough and

the door sill having a passageway therethrough to the exterior of the vehicle and communicating with the door passageway, means forming a passageway from the door passageway to said inlet space, said passageways being effective when the door is closed to supply air from the exterior of the vehicle to said inlet space to the blower therein, and means within the door for filtering the air before delivery to said blower space.

5. An automobile heating assembly comprising a box-like casing open at its upper end adapted to be inserted downwardly through a hole in an automobile floor to be suspended in position below the floor, a heater core having inlet and outlet nipples extending laterally from one end thereof, said casing having vertical guideways along opposite side walls and being shaped for sliding engagement of said heater core along said guideways for ready insertion of said core downwardly into said casing or removal therefrom through its open upper end, said heater core when within said casing dividing said casing into an air receiving space and a heated air delivery space communicating with the automobile interior, a blower within said air inlet space for blowing heated air from said heater core into said outlet space and into the automobile interior, said heater core nipples being adapted to receive heating medium conducting pipes.

6. In an automotive vehicle, a heater assembly therefor comprising a box-like casing entirely open at its upper end and having laterally extending supporting flanges at its upper edge, said casing being insertable through a single opening in the floor of the vehicle for engagement of the casing flanges with the floor for suspension of the casing below the floor, a heater core within said casing extending transversely thereof to divide the casing into an air inlet space and an air outlet space communicating through the upper end of the casing with the interior of the vehicle, and a blower in the air inlet space for blowing heated air from the heater core through the air outlet space and into the vehicle body, said casing having guideways thereon on which said heater core may be readily slid into the casing or withdrawn therefrom through the casing open end.

ELBERT L. POTTER.
